REBOUND CHECK FOR SHUTTLES

William Hunt, Fall River, Mass., assignor, by direct and mesne assignments, to William Hunt, Frank Medeiros, and Edward J. Houle, jointly as copartners doing business as Hunt, Medeiros & Houle Company

Application November 19, 1942, Serial No. 466,198

2 Claims. (Cl. 139—185)

This invention appertains to new and useful improvements in looms and more particularly means for checking shuttles against rebound movements.

An important object of the present invention is to provide means for stopping a shuttle in the proper position in a shuttle box in order to preclude any rebound motion and in order that the shuttle always be uniformly in position to be struck by the picker stick.

Another important object of the invention is to provide a rebound stopping device for loom shuttles which in use will serve to eliminate the necessity of a considerable number of adjustments that now take the time of loom fixers.

Still another important object of the invention is to provide a shuttle checker cooperating with the usual protector rod, which serves to carry the binder fingers, whereby in the event the usual spring of the protector rod becomes inoperative the improved means for checking the shuttle will also serve to set the conventional dagger.

Other objects and advantages of the invention will become apparent to the reader of the following description.

In the drawings:

Figure 1 is a fragmentary side elevational view showing portions of a conventional loom with the improvement applied.

Figure 2 is a fragmentary top plan view showing a shuttle box and the present invention associated therewith.

Figure 3 is a fragmentary elevational and sectional view showing a shuttle box in section and associated mechanism in conjunction with the present invention, the binder finger shown in shuttle holding position.

Figure 4 is an elevational and sectional view similar to that of Figure 3, but showing the lay moved away from the spring element of the present invention.

Figure 5 is a perspective view showing a protector rod, etc., in conjunction with the spring of the present invention.

Referring to the drawings wherein like numerals designate like parts, it can be seen that numeral 5 denotes a loom frame to which the elements of the present invention generally referred to by numeral 6 are attached.

Numerical 7 generally refers to a lay on which are box structures at the ends thereof as shown in Figure 1 and generally referred to by numeral 8.

Each of these box structures 8 comprises a

box front 9 and a binder 10, the box front 9 having slotted lugs 11 through which machine screws 12 are disposed and driven into the lay. By loosening and tightening these machine screws 12, suitable adjustment of the box front 9 can be attained.

As shown in Figures 1 and 2, each box 8 has a picker stick 13 operative therein. Further, each binder 10 has a spring 14 for exerting normal pressure thereon. As is conventional, the binder 10 which is flexible and anchored at one end as at 15, has a belly 16, which the usual shuttle 17 acts on when entering the box 8 to lift the usual dagger to an elevated position out of the path of the usual stop frog.

Now referring to additional details of the conventional machine, it can be seen in Figure 5, that numeral 19 denotes an elongated protector rod having laterally disposed foot portions 20, 20 at the ends thereof. On the foot portions 20 are adjustably secured fingers 21, 21 which bear against the binder 10 as suggested clearly in Figures 3 and 4. The rod 19 carries a dagger 22 which is cooperative with a frog 23 situated on the loom frame or some supporting structure.

As is understood, the lay 7 moves toward the right and left as illustrated in Figures 3 and 4. The present invention is associated with the rod 10.

30 In carrying out the present invention, an angle plate 24 is attached to the loom frame 5. This angle plate 24 has a slot 25 therein and a machine screw 26 is disposed through this slot and into a threaded opening in the frame 5. With this means the plate 24 can be easily adjusted. Rising from the outstanding portion of the angle plate 24 is an elongated spring 27 having a curved upper end portion, curved in the direction away from the adjacent foot portion 20 of the protector rod 19.

Referring again to Figure 5, it can be seen that spring means is associated with the protector rod 19 for normally maintaining the binder fingers 21 pressing against the binders 10. 45 This spring means consists of an adjustable collar 28 and a spring 29 coiled about the rod 19 and anchored to some stationary structure as at 30.

It can now be seen that with the lay 7 moving toward the right in Figure 3, the near foot 20 will engage the upper curved end portion of the spring 27. However, just before this takes place and as the lay reaches in full extent of movement, the shuttle drives into the box. Almost simultaneously the foot 20 shown in Fig-

ure 3 rides the curved upper end of the spring 27, rocking the protector shaft 19 and causing the fingers 21 to exert additional sudden pressure for but the slightest moment, just before the lay starts in the opposite direction. This action serves to stop the shuttle as it reaches its fullest insertion in the box and serves to prevent any rebound of the shuttle. This action of the fingers 21 is very sudden and of the minutest duration and is more in the nature of a "tap" just enough to stop the shuttle as it reaches the proper position in the box and before it can pursue any rebound movement.

Obviously, many smashes and other loom disturbances are caused by rebound positions of shuttles with the result that the full force and effect of the picker sticks is not and, of course, cannot be utilized when the shuttles are improperly positioned in the boxes. However, with each shuttle stopped at its most efficient position in the boxes a high percentage of loom disturbances will be eliminated.

Another advantage of the present invention resides in the fact that should the spring 29 become disrupted on the protector bar 19 and a shuttle not enter its box, obviously, action of the foot 20 against the spring 27 will act to push the binder 10 much farther into the box and upon the return movement of the lay and before the protector rod 19 and dagger 22 have had an opportunity to resume the position shown

in Figures 3 and 4, the dagger will have struck the frog 23 to automatically stop the loom without the assistance of the spring 29.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In combination with the rotatably mounted protector rod of a loom, and spring means tending to rotate the rod in one direction, a lateral protuberance on said rod, and a stationarily mounted member adapted to be struck by the protuberance and impart a sudden momentary increment of rotation to said rod in said one direction.
2. In a loom, a shuttle box including a binder, a rotary protector rod provided with a binder finger and spring rotated in one direction to press said finger against the binder, a lateral protuberance on the protector rod, and a stationarily mounted leaf spring against which the protuberance is adapted to strike and be deflected to impart a sudden momentary increment of rotation to said rod in said one direction and to exert additional pressure by said finger against said binder.

WILLIAM HUNT.
